PENCIL CONSTRUCTION

William E. Hoffmann, University City, Mo.

Application January 17, 1942, Serial No. 427,112

5 Claims. (CL 120—83)

The present invention relates generally to pencils and more particularly to novel pencil and pencil lengthener constructions.

An object of the present invention is to provide a novel pencil construction which is economical in the initial use of graphite and which is adapted to be substantially used up in writing.

Another object is to provide a novel pencil lengthener which is adapted to give added use to pencils and which is adapted to prevent destruction thereof in a pencil sharpener.

Another object is to provide a novel pencil and pencil lengthener construction which is adapted to utilize substantially the full graphite content of the pencil.

Another object is to provide a novel pencil which includes an eraser mounted by means of an internal connection.

Another object is to provide a novel pencil of standard consumable construction which incorporates a removable replaceable eraser.

Another object is to provide a novel pencil and pencil lengthener construction for utilizing the full graphite content of the pencil without injury to the lengthener, or to the cutter of the pencil sharpener.

Another object is to provide a novel pencil and pencil lengthener construction in which the lengthener is attached to the pencil by means of the normal eraser support and in which the lengthener incorporates means for carrying the normal eraser of the pencil.

Another object is to provide a novel pencil and pencil lengthener construction in which the initial amount of graphite employed is less than that in a standard pencil and in which substantially the whole graphite content of the pencil is available for writing purposes.

Other objects and advantages are apparent from the following description taken in conjunction with the accompanying drawing in which:

Fig. 1 is a plan view of a pencil constructed in accordance with the present invention;

Fig. 2 is a view of the pencil shown in Fig. 1 reduced to stub size through sharpening;

Fig. 3 is a section on the line 3—3 of Fig. 2;

Fig. 4 is a plan view of a pencil lengthener constructed in accordance with the teachings of the present invention;

Fig. 5 is a plan view of the lengthener shown in Fig. 4 and the pencil stub shown in Fig. 2 operatively engaged for writing purposes;

Fig. 6 is a view partly in central section and partly in plan of the pencil stub and pencil lengthener construction shown in Fig. 5;

Fig. 7 is an enlarged view of the connecting or eraser supporting member; and

Fig. 8 is a view of the pencil and pencil lengthener construction disposed in the opening of a pencil sharpener.

Referring to the drawing more particularly by reference numerals, 10 indicates generally a pencil constructed in accordance with the teachings of the present invention which includes a body 11, graphite 12 (Fig. 3), an eraser supporting member 13, and an eraser 14.

The member 13 includes spiral threads 16 which terminate a short distance from the upper end 17 of the body 11 at a junction with an axial thread 18. A reduced portion 19 of the member 13 occupies the upper portion of the bore 20 receiving the graphite 12, and is enlarged slightly at 21 to form an anchor for the member 13.

20 Referring to Figs. 4—7, 25 indicates generally a pencil lengthener constructed in accordance with the teachings of the present invention. The lengthener 25 includes a body portion 26 having an enlargement 27 spaced from one end 28. An 25 eraser supporting member 29 identical externally with the member 13, which, therefore, requires no particular description, extends from the other end 30 of the body 26. The portion 26, the enlargement 27, and the member 29 preferably are 30 an integral unit, as of plastic, although they may be separate elements. When separate, member 29 may be anchored in any suitable manner. In the end 28 is a threaded well 32 (Fig. 6), the threading terminating short of the actual face 35 of the end 28, providing an enlarged non-threaded portion 33.

In use, the pencil 10 becomes gradually shorter through sharpening until it becomes a stub as is illustrated by Fig. 2. At this stage, the stub 40 is difficult to use, for it is too short for the hand. Since the pencil 10 is constructed with the member 13 supporting the eraser 14, the eraser 14 is removed and the pencil lengthener 25 is applied to the member 13 by the simple threading operation afforded through the threads of the well 32 engaging the threads 16 of the member 13. The enlargement 33 of the well 32 obviates interference with the axial thread 18. The eraser 14 is then placed on the support 29. The pencil and 50 pencil lengthener forms a cooperative construction to assure further comfortable use of the stub pencil.

Furthermore, the stub pencil may be sharpened in a pencil sharpener of a type such as the electrical sharpener 35 shown in Fig. 8 as the point

becomes dull, and this sharpening may be effected without fear of injuring the cutters since the enlargement 27 prevents the pencil 10 and pencil lengthener 25 from progressing into the opening of the pencil sharpener 35 beyond a predetermined point, which point manifestly prohibits contact of the member 13 and the end of the body 26 with the cutters.

It is to be observed that the axial thread 18 of the member 13 provides a lock for the eraser 14 thereby preventing accidental removal of the eraser 14. The resilience of the material of the eraser 14 cooperates with the axial thread 18 to prevent an unscrewing action unless a sufficient force is applied.

It is also to be noted that the reduced extremity 19 of the member 13 occupies a portion of the bore receiving the graphite 12, thereby effecting economy in the graphite employed initially in the construction of the pencil 10. It is clear that even with a lengthener 25 as shown, this portion of graphite replaced by the reduced extremity 19 could not be sharpened for use in any mechanical sharpeners now in use.

The enlargement 27 combines comfort with its stopping function. It is streamlined to reduce any distorting effect due to the greater diameter thereof.

Since the eraser 14 is not sheathed in any respect, it may be used sidewise or from the end. With soft erasers, it is quite often handy to employ the side portion in erasing. With the present construction, there is no danger of cutting the sheet, or the like, in using the side of the eraser since exterior metal is not employed. Hence, a maximum of the eraser 14 is afforded.

It is, of course, apparent that certain changes in form and material may be effected without departing from the present invention.

It is to be understood that the foregoing description and the accompanying drawing are given by way of illustration and example and not for purposes of limitation, the invention being defined by the claims which follow.

I claim:

1. A pencil lengthener comprising a body, means at one end to receive a pencil, and stop means connected to the body spaced from the said one end adapted to limit the travel of the lengthener into the receiving opening of a pencil sharpener.

10 2. A pencil lengthener comprising a body, means at one end to receive a pencil, said means comprising a well which is threaded to within a predetermined distance from the extreme outer end thereof, and stop means connected to the body spaced from the said one end adapted to limit the travel of the lengthener into the receiving opening of a pencil sharpener.

15 3. A pencil lengthener comprising a body, means at one end of the body to receive a pencil, and an enlargement connected to the body spaced from the said one end of the body adapted to limit the travel of the lengthener into the receiving opening of a pencil sharpener.

20 4. A pencil comprising a body, a member connected to one end of the body by extending a predetermined distance into the area normally occupied by the graphite, said member including spiral threads to within a short distance from the end of the body and an axial portion of thread from such point to the body, said spiral and axial threading being adapted to receive 30 an eraser in locking relation.

25 5. A pencil comprising a body, a member, and a connecting means, said body being secured to said connecting means by the extension of one end of said connecting means a predetermined distance into the area of said body normally occupied by the graphite, said connecting means including spiral threads to within a short distance from the end of said body and an axial portion of thread from such point to the body, said spiral and axial threads being adapted to receive 40 said member in locking relation, and thereby connecting said body and said member in secure relationship.

WILLIAM E. HOFFMANN.
